Filed Feb. 27, 1975, Ser. No. 542,468

Term of patent 14 years

Int. Cl. D2—02; D24—04
U.S. Cl. D83—1 J

FIG. 1 is a pictorial view of a kidney support belt showing my new design and in particular one side thereof;

FIG. 2 is a pictorial view of the other side of the kidney support belt; and

FIG. 3 is an enlarged pictorial view of a portion of the open mesh material, of which the kidney support belt is made.

The dash lines in the different views represent stitching.
I claim:

The ornamental design for a kidney support belt, as shown and described.
